UNITED STATES PATENT OFFICE.

VICTOR ALVIN SMITH, OF ROCKPORT, MISSISSIPPI.

MOSQUITO-BAR.

1,226,401.

Specification of Letters Patent. Patented May 15, 1917.

Application filed August 17, 1916. Serial No. 115,355.

To all whom it may concern:

Be it known that I, VICTOR A. SMITH, a citizen of the United States, and a resident of Rockport, in the county of Copiah and State of Mississippi, have invented a new and Improved Mosquito-Bar, of which the following is a full, clear, and exact description.

My invention relates to a mosquito bar.

10 The object thereof is to provide a collapsible bar which can be secured to the frame of a bed so that it may be easily and quickly placed into operative or into inoperative position.

15 With the above and other objects in view, the nature of which will more fully appear as the description proceeds, the invention consists in the novel construction, combination and arrangement of parts as herein 20 fully described, illustrated and claimed.

In the accompanying drawings, forming part of the application, similar characters of reference indicate corresponding parts in all the views.

25 Figure 1 is a perspective view of a bed provided with an embodiment of my invention;

Fig. 2 is a fragmentary plan view of the yielding frame structure of the bar; and

30 Fig. 3 is a perspective view showing the bar in the inoperative position.

Referring to the drawings, the mosquito bar 5 is reinforced at the border by a tape 6 which helps to fit the bar more closely 35 about a bed. A yielding rod 7 of suitable material is secured to the head of the bed by suitable securing members 8. The length of the rod 7 is such that when strained the free end thereof can be brought substantially above the middle of the bed. The free 40 end 9 of the rod 7 is apertured. Tapes 10 are secured to the apertured end 9 with one end thereof. The other end of each of said tapes is secured to the tape 6 adjacent that

45 part of the bar which forms a corner on the bed when the bar is fitted thereover. At the junction of the tape 10 with the tape 6 a button 11 is provided to be engaged by an eye 12 carried by an elastic tape 13 which 50 is secured to the rod of the bed. These elastic tapes 13 maintain the bar in operative position on the bed.

A pair of crossing steel ribs 14 are secured at their crossing to the rod 7 adjacent its free end. The ends of said ribs 14 have openings into which an end of an elas-

tic webbing 15 is secured. The other end of the webbing is secured to a tape 10 which extends in the direction of the corresponding rib. The elastic webbing 15 is secured 60 to the tape 10 substantially midway between the rib 14, to which the webbing is secured, and the reinforcing tape 6 to which the tape 10 is secured. These elastic webbings help 65 to shape the top of the bar, as they deflect the ribs when the mosquito bar is secured to the elastic tapes 13. They also help to draw the bar off the head of the bed when the mosquito bar is placed into inoperative position by detaching the bar from the elastic tapes 13.

When the mosquito bar is released by the elastic tapes 13 the yielding rod 7 returns to its normal upright position, thereby drawing the mosquito bar on the yielding 75 rod 7. The ribs 14 also return to their normal straight form substantially in the plane of the rod 7, and also help to draw the mosquito bar. The elastic webbing 15 draws up the lower part of the mosquito bar to a 80 point above the head of the bed, as shown in Fig. 3.

The mosquito bar covers the rod 7, ribs 14 and the tape 10. The elastic webbing is preferably placed above the mosquito bar, 85 but if desired it can also be placed under the mosquito bar.

It will be seen that the mosquito bar can be easily and quickly placed into operative or into inoperative position due to the fact 90 that the yielding rod and the ribs flex easily when pull is exerted thereon, and, consequently, the bar resumes its proper shape on the bed automatically when placed into operative position. When it is in inoperative 95 position it occupies very little space at the head of the bed, as it is maintained substantially in a plane with the head of the bed, as will be seen from Fig. 3.

I claim:

1. A mosquito bar for beds comprising a yielding, normally straight rod one end of which is adapted to be secured to the head of the bed, a netting forming the bar, tape reinforcing the netting at the margin, tape 105 connecting the free end of the yielding rod to the reinforcing tape, elastic members for securing the reinforcing tape to the bed whereby the bar is maintained in operative position, and elastic webbing for gathering 110 the bar toward the free end of the rod when the bar is in inoperative position.

2. A mosquito bar for beds, comprising a yielding, normally straight rod one end of which is adapted to be secured to the bed, crossing, yielding, normally straight ribs secured at their crossing to the free end of the rod, a netting forming the mosquito bar, tape reinforcing the bar at the margin, tape connecting the free end of the yielding rod to the reinforcing tape at points of said reinforcing tape which are to be located at the corners of the bed, elastic members for securing the reinforcing tape to the bed whereby the mosquito bar is maintained in

operative position on the bed, and elastic webbing connecting the ends of the yielding ribs to the tape, said elastic webbing being adapted to deflect the ribs and give shape to the bar when the same is in operative position and to gather the bar toward the free end of the rod when the bar is placed into inoperative position.

VICTOR ALVIN SMITH.
